UNITED STATES PATENT OFFICE.

DAVID C. LASH, OF SHIRLEY, MASSACHUSETTS.

GARTER.

Application filed September 12, 1921. Serial No. 500,030.

To all whom it may concern:

Be it known that I, DAVID C. LASH, a citizen of the United States of America, and resident of Shirley, in the county of Middlesex and State of Massachusetts, have invented new and useful Improvements in Garters, of which the following is a specification.

The present invention relates to garters of the type having a web and a fastener connected together and more particularly to a connector for interconnecting said parts. While the invention is particularly applicable to men's garters where both ends of the web are attached to the connector it is also applicable to women's garters where only one end of the web is attached to the connector, the other end being attached to some article of apparel.

Heretofore it has been customary to make the connector in the form of a fabric pad with the fasteners and one end of the web permanently stitched thereto, and in men's garters with a hook (or eye) also sewed thereon for attachment with the other end of the web. The fabric pad is composed of several layers which must be folded and assembled and then sewed together. All this folding, assembling and sewing adds materially to the cost of the garter and any defect in the sewing renders the article short lived. And with such construction it is not practicable to rip the parts asunder to wash the web when soiled or to replace the web when it loses its elasticity. Moreover the angular relationship between the web and pad is fixed so that the web cannot be adjusted, without wrinkling, to make different angles with the connector, thereby to be fitted either to a long slender leg where the web meets the connector at a sharp upward inclination or to a fat leg where the web meets the connector more nearly horizontally.

Objects of the present invention are to eliminate the aforesaid folding, assembling and sewing, to make the connector more sanitary and at the same time more durable, to make the web readily adjustable in length, to make the web readily detachable for washing or replacement, to make the web and connector angularly adjustable in relation to each other at both ends of the web, to reduce the number of metallic parts, to avoid metallic parts on the inner side of the garter, to make the garter thin and flat

so as not to push out the outer clothing of the wearer when the clothing is drawn tightly thereover, and in general to provide a garter which will last many times longer than the ordinary garter except the web which may be readily replaced.

A cardinal aspect of the invention consists in joining the fastener and web together with a plate instead of the ordinary fabric pad, the plate being flexible to permit more or less flexure in attachment and detachment of the garter and in use, especially in men's garters where the connector frequently fits over the shin bone, but being sufficiently stiff not to be otherwise distorted in use. The plate should also be non-rusting to withstand the action of perspiration. While certain objects of the invention may be attained by making the plate of hard rubber, wood fiber or other composition, or even of metal, I preferably employ celluloid inasmuch as it is water-proof and non-abrasive on the web or clothing and presents a smooth and handsome appearance.

In another important aspect the invention involves a unique interconnection of the connector and the other parts of the garter. In the preferred embodiment the plate is slotted to receive both the fastener and one end of the web, and the web is secured to the plate solely by friction. This frictional attachment can best be effected by providing two juxtaposed parallel slots in the plate, these slots defining a bar therebetween, and by looping the web around the bar through the slots with its free end frictionally held between the plate and the web. In the case of men's garters the hook (or eye) attached to the other end of the web is also preferably secured in place solely by friction.

In order more clearly to illustrate the nature of the invention I have shown preferred embodiments thereof in the accompanying drawings, in which—

Fig. 1 is a front view of one embodiment; 100
Fig. 2 is a section on line 2—2 of Fig. 1;

Fig. 3 is a section on line 3—3 of Fig. 1;

and

Fig. 4 is a front view of a different embodiment, a portion of the web being broken away.

The particular embodiment illustrated in Figs. 1, 2 and 3 comprises a fastener F of any suitable construction, a web W which is ordinarily elastic, a connector C for inter-

2 connecting the fastener F and one end of the web W, and an eye-member I adapted to hook over a stud H on the connector C.

The embodiment shown in Fig. 4 differs only in the shape of the connector C', the fastener F', web W', eye-member I' and stud H' all being identical with the parts correspondingly designated in the preceding figures.

As above indicated one of the principal features of the invention consists in interconnecting the fastener F and web W with a plate instead of the ordinary fabric pad. Thus in the figures I have illustrated the connectors C and C', as plates. The connecting plate may be shaped in various ways but the two shapes illustrated in Figs. 1 and 4 I consider the best shapes. The plate is preferably formed of celluloid and the stud thereon is also preferably formed of celluloid, these two parts being secured together by any suitable celluloid cement but preferably with a cement which comprises celluloid solvent so that the contacting surfaces of the parts are softened in the cementing process and practically welded together.

The aforesaid slotted connection between the connector and the fastener and web is preferably effected as illustrated in Figs. 1, 3 and 4 where X and Y represent juxtaposed parallel slots defining therebetween a bar Z integral with the plate C. The web W is looped around the bar Z through the slots X and Y and the free end w extends between the plate C and the web W so that the web is held in position on the connector by means of the frictional engagement between the web and the plate.

The slot Y is preferably made slightly shorter than the width of the web and the slot X slightly wider. This permits adjustment of the angular relationship between the web and connector so that the garter may be adjusted without wrinkling to either a fat leg or a slender leg. By making the slot Y shorter than the width of the web the end of the web is held in the slot more tightly and in case the web is adjusted to make an angle with the slots differing more or less from a right angle the folded-under end of the web does not project from beneath the web.

The fastener F is preferably connected to the plate C by means of a loop extending through a single slot S in the plate. The fastener slot S and the web slots X and Y are arranged obliquely with respect to each other to make a better fitting garter.

The web W is preferably connected to the eye-member I in the same way that it is connected to the plate C, as shown in Fig. 2. For this purpose the member I is provided with slots preferably disposed closely adjacent to each other and of the same relative character as the slots X—Y of

the plate C. The eye-member I may be formed of any suitable material but it is preferably formed either of celluloid or metal.

With this construction the parts may be put together or taken apart quickly without the use of a sewing machine or other machine, and the web may be readily detached from the other parts for the purpose of being washed or replaced. Thus the elastic portion of the garter, which is the most perishable portion, may be replaced when worn out, thereby renewing the garter at a small fraction of the cost of a new one.

From the foregoing it will be evident that the studs H and H' and the eye-members I and I' constitute separable connecting elements adapted to be hooked together and unhooked in well-known manner.

I claim:

1. A garter comprising a fastener, a web, and an integral plate of flexible material for connecting the web and fastener, said plate having a slot near its lower edge for reception of the fastener, a pair of juxtaposed web-receiving slots near its upper part, said slots extending obliquely to said first slot, and a connecting element at the central part of the plate.

2. A garter having a fastener, a web, and a plate of flexible celluloid forming a connector therefor, said plate having means for securing the fastener thereto and a pair of juxtaposed slots for the reception of the web, one of said slots being shorter than the other, the length of the shorter slot being less than the width of the web.

3. A garter comprising a web, a connecting element secured to one end of said web, and a plate provided with a connecting element cooperable with said first connecting element, said plate having a pair of juxtaposed slots near one of its edges for reception of the web, the slot further from the edge being longer than the other and the web passing over the front surface of the plate and the shorter slot and rearwardly through the longer slot, then against the rear face of the plate and forwardly through the shorter slot.

4. A garter comprising a fastener, a web, and a connector interconnecting the web and fastener, the connector having juxtaposed slots to receive the web, the slots extending in the same general direction as one side of the connector and the slot nearer said side being of less length than the width of the web.

5. A garter comprising a fastener, a web, and a connector interconnecting the web and fastener, said connector having a slot near its lower edge for the reception of the fastener, and juxtaposed slots to receive the web, said latter slots being oblique to the first slot, one of the latter slots being shorter

than the width of the web and the other slot being at least substantially as long as the width of the web.

6. A garter comprising a fastener, a web, and a connector interconnecting the web and fastener, the connector having a slot for the reception of the fastener, and juxtaposed slots to receive the web, the latter slots extending obliquely to the first named slot and in the same general direction as one side of the connector, the slot nearer the said side being shorter and wider than the other, the shorter slot being less in length than the width of the web.

15 7. A garter having a fastener, a web, a flexible plate connector, and a connecting element, the connector and said element each having parallel juxtaposed slots and each end of the web extending first through one

slot and then through the juxtaposed slot 20 with the free end underlying the web, whereby the web may be detachably held for ready replacement.

8. A garter comprising a stiff but flexible plate connector, a fastener secured near one side of the connector, a web member having one of its ends secured to the connector and provided at its other end with a connecting element, and a second connecting element 25 outstanding from said connector near its center and cooperating with the connecting element at the end of the web for holding a garter in position upon the leg of the wearer.

Signed by me at Boston, Massachusetts, 35 this 7th day of September, 1921.

DAVID C. LASH.
